UNITED STATES PATENT OFFICE.

CHARLES W. JOYNT, OF MAKANDA, ILLINOIS.

FIRE-ESCAPE.

SPECIFICATION forming part of Letters Patent No. 311,661, dated February 3, 1885.

Application filed May 1, 1884. (No model.)

To all whom it may concern:

Be it known that I, CHARLES W. JOYNT, of Makanda, in the county of Jackson and State of Illinois, have invented a new and Improved 5 Fire-Escape, of which the following is a full, clear, and exact description.

My invention relates to the class of fire-escapes employing folding-ladders as means for descending to the ground; and it consists in a 10 ladder formed of series of parallel side rods provided at their lower ends with right-angled sockets for receiving the ladder-rounds, and at their upper ends with eyes for receiving the round of the adjoining section of the ladder.

15 Reference is to be had to the accompanying drawings, forming part of this specification, in which similar letters of reference indicate corresponding parts in all the figures.

Figure 1 shows the position of the box for 20 holding the ladder. Fig. 2 shows the ladder unfolded in condition for use. Fig. 3 shows the ladder folded. Fig. 4 is a detail view of the adjoining ends of the ladder-sections; and Fig. 5 is a sectional view of one of the joints.

25 My improved fire-escape ladder is formed of side rods, A, each having formed on one end an eye, a, and provided at the opposite end with a right-angled socket, b, the wooden or tubular-iron round B entering the sockets 30 of two such rods, and receiving the eyes a of the rods of the adjoining section, and stops c secured to the rounds B, and confining the eyes a in their place adjoining the right-angled socket b. The sections of the ladder decrease

35 in width and length toward the free end thereof, and are capable of being compactly folded one within the other, forming a pyramidal

pile, as shown in Fig. 3. The ladder thus folded is placed in the box C at the window, where it remains until required for use. The ladder 40 is suspended by two hooks or straps, D, which extend over the window-sill. The rounds B are secured in the sockets b by screws passing through the side of the socket, or in any other convenient manner, and the stops c may be attached to the rounds in the same way, or they 45 may be formed integral with the round.

For extra length a double ladder can be provided. At the lower or last section of escape 50 may be attached a second ladder, at D, which will fold in the same manner as first escape, and may be put in box requiring space of twice the depth of the single ladder, which will not exceed over two and a half inches.

Having thus described my invention, what 55 I claim as new, and desire to secure by Letters Patent, is—

1. A fire-escape ladder formed of rods A, provided with eyes a, the right-angled sockets b, secured to the rods A, and the rounds B, entering the sockets b and secured therein, as 60 described.

2. The combination, with a ladder formed of rods A, having eyes a, the right-angled sockets b, and the rounds B, of the hooks or 65 straps D and box C, as described.

3. The combination, in a fire-escape ladder, of the rods A, having eyes a, the right-angled sockets b, rounds B, and stops c, as described.

CHARLES W. JOYNT.
